UNITED STATES PATENT OFFICE.

HORACE B. GALE, OF NATICK, MASSACHUSETTS, ASSIGNOR TO SUBMARINE SIGNAL COMPANY, OF WATERVILLE, MAINE, A CORPORATION OF MAINE.

SOUND-PRODUCING DEVICE.

946,029.

Specification of Letters Patent. Patented Jan. 11, 1910.

Application filed March 3, 1904. Serial No. 196,253.

To all whom it may concern:

Be it known that I, HORACE B. GALE, of Natick, in the county of Middlesex and State of Massachusetts, a citizen of the United States, have invented a new and useful Improvement in Sound-Producing Devices, and do hereby declare the following, in connection with the accompanying drawings, to be a full, clear, and exact disclosure of my said invention.

This invention relates to a sound producing device for use in a submarine signaling system for signaling from vessel to vessel or shore, or vice versa, whereby a vessel may be guided on its course or its locality readily determined.

The particular object of my invention is the production of actuating means for the submerged sounder, such means to be easily operated, and yet powerful in action, to be susceptible of operation in response to code or other predetermined succession of actuating impulses, and to be so simple and reliable as to be readily operated by unskilled persons and to require little attention or repair.

The feature of my invention is the operation of the bell striker or equivalent means by a piston or plunger, preferably directly attached thereto. The means by which this piston is itself actuated and the means by which the actuating means is controlled for code or other signaling also form important features of my invention as will hereinafter more fully appear.

Heretofore in submarine signaling various means have been employed for vibrating the sounder. Electro-magnets have been used for this purpose, but the practical utility of such is somewhat limited for several reasons. For instance, electrical apparatus is peculiarly liable to injury by immersion in salt water, and, furthermore, in the isolated locations where signaling apparatus is frequently employed, requires for its operation a complete engine and dynamo plant and other more or less complicated mechanism, all of which may in unskilled hands, cause the apparatus to fail at a critical time. My piston-operating mechanism on the other hand is not liable to failure for any such reasons. It requires no elaborate plant for its operation; it is easily constructed, injured with difficulty and requires no skilled

attendant to insure its continued and successful operation.

The particular form of sounding device does not in itself constitute the essence of my invention; my operating means is adapted for use in connection with various of such devices. I prefer, however, to employ a metallic resonating body, which may be conveniently made in the form of a bell, and a hammer or striker, preferably of metal, for delivering blows upon the resonator. In such case the motion of the striker, being reciprocating or oscillating in character, can best be controlled by means of a reciprocating motor, the strokes of which correspond to the strokes of the striker. The resonating body should be in direct contact, either with the water through which the signaling is conducted, or with a contiguous body of liquid, to which the signals are delivered.

Having set forth the object and nature of my invention, I will now describe the same more particularly in connection with the drawings in which—

Figure 1 is a diagrammatic representation of the device in a form especially adapted to be suspended in the water from a ship such as a lightship lying at anchor. Fig. 2 illustrates, also in diagrammatic form, a modification of the automatic controlling means.

By the chain *c* and intermediate mechanism presently to be described is hung the bell *B* submerged in the water and suspended below the water line indicated at *A*—*A*. Suitably mounted within the bell and in operative relation thereto is the hammer or striker *S*. Located intermediate the chain and the bell is the cylinder *C*, within which is located the piston *P* adapted to have reciprocating motion therein. The piston is provided with the extension *p* operating in the dash-pot *D* to control the movement of the piston. Connected with the piston for movement therewith is the rod *R* extending through the bell support *r* and provided at its lower end with the yoke *Y*. The yoke *Y* interlocks with the pin *a* upon a bell-crank extension of the striker for operating the striker. The engagement of the two is such as to permit, when in operation, of a slight relative movement whereby the hammer may, after each stroke, fall back from the bell as shown in the dotted position *S'* instead of remaining in contact therewith.

Attached to, or forming part of the cylinder casing C is the hollow elbow E communicating with the chamber of the cylinder; at a point thereof immediately above the dash-pot extension in this elbow, and communicating with the interior thereof, is a vent or port controlled by the check-valve m, the function of which will presently appear. Attached to the elbow E in any suitable way and serving as an extension thereof is the tube H, preferably a flexible hose. This tube is supported at or near the water line by an attachment b to the chain c. Above the water line the passage communicating with the cylinder C is continued by the tube h leading to a valve casing V and opening into the same at k. Said casing may be located on shipboard or elsewhere according to circumstances. This casing is provided with a piston chamber having the inlet port q and exhaust port x. Within said chamber the valve v is adapted to reciprocate, its downward movement being shown as accomplished by the coil spring s and its upward motion by the cord or other connection w, controlled by means presently to be described. The piston is shown in the drawings as being held at the top of its stroke against the action of the spring, the tube h being then in communication with the exhaust x. When released to obey the action of the spring, the piston is forced downward with a quick movement to a position below the point k, whereupon the tube h is in communication with the inlet port q.

It is necessary that the valve v should have a quick movement in this direction in order to admit the full pressure of the working fluid to the cylinder C, so as to produce a quick, powerful stroke of the piston P and of the striker S. It is not necessary, however, that the forward stroke of the valve v should be made quickly as this movement by opening the passage h to the exhaust passage x, controls the return stroke of the piston P and the striker S, which stroke not being intended to strike the bell can be made slowly.

I prefer to control the action of the spring s through a suitable connection w by code mechanism. Two forms of such mechanism are shown in Figs. 1 and 2. In Fig. 1 I have shown the wheel W adapted to be rotated in the direction of the arrow by any available motor power such as steam engine, clock-work, or other means. This wheel has a series of notches n in its periphery and any or all of these notches are adapted to be closed by pieces t to produce any desired signal as hereinafter set forth. Mounted upon a pivot g² is the lever g, to which the connection w is attached in any suitable manner. In fixed relation to the lever g and adapted to turn therewith is the lever l. Affixed to the end of the lever l is a detent o.

The tension of the coil spring s acting upon the lever g through the connection w causes the detent o to bear against the periphery of the wheel W. The spring is thus normally held in the position shown in the drawing. When, however, a notch n passes beneath the detent o the spring is instantaneously released, allowing it to act upon the piston v. The return stroke of the valve v is accomplished by the further movement of the code wheel W bringing the rear side of the notch against the lever l and thereby pushing the same back, to return the parts to the position shown; as the action of the code wheel is necessarily rather slow the valve v is opened gradually and not instantaneously on this stroke. By opening or closing certain of the notches n with the pieces t the frequency or succession with which the spring s is thus released may be varied at will and the particular signal thereby changed.

In Fig. 2 of the drawings is shown another form of my code-signaling device. In this figure the connection w is attached to the spring in the manner heretofore described, and its other end to the lever g¹ corresponding to the lever g of Fig. 1. Instead of the rotating wheel having its periphery notched, however, I have shown in this figure the wheel W¹ as having a series of pins T projecting from one face thereof and adapted to co-act with the arm l¹ of the lever for operating the connection w to release and compress the spring s, as heretofore set forth. The pins T are removable and by removing or rearranging them any desired signal may be produced. In the drawing the white circles indicate the pins and the dark circles the holes from which the pins have been withdrawn, the arrangement shown being adapted to cause the bell to strike the number 312. Other forms of stops may be substituted for the pins, the function being the same.

It is evident that the details of this invention may be considerably varied while preserving its essential features. Such variations will occur to anyone skilled in the art.

The operation of the device is as follows:—Upon submerging the apparatus the check valve m opens, causing the tube H to be filled up near the water line A—A with water. Provided the signal is to be operator by code, the wheel W is then rotated, causing the spring s to be alternately compressed and released in the manner hereinbefore stated. The piston v, being normally in the position shown in the drawing, when released descends below the point k, whereupon the working fluid, which may be steam, compressed air, or other suitable fluid, passes through the connection q into the tube h and acting upon the water in the tube H causes such water to act upon the bottom of

the piston P to raise the same. The upward motion of the piston P is provided for by the vent o^1 at the top of the chamber C and such upward motion of the piston causes a 5 similar motion of the connection R, whereupon the striker S is thrown from the position shown in the full lines, against the opposite side of the bell, causing the same to resound. The play allowed for by the 10 yoke Y and pin a permits the striker to thereupon fall back to the dotted position S¹. The spring s is then again compressed by the action of the wheel W, and the piston v raised to the position shown in the 15 drawings. This opens the tube h to the exhaust passage w, thereby releasing the pressure in the tubes h, H and chamber C. The weight of the piston P and striker S then forces the water in the tube H back to 20 its original level A—A, the piston P returning to the bottom of its stroke and the striker returning to the position S. Before the piston P reaches the bottom of its stroke, the dash-piston p enters the dash-pot D, in 25 which it is fitted somewhat loosely, the fluid imprisoned beneath it escaping by leakage around the piston and serving to check the momentum of the moving parts so that the striker does not deliver a blow upon the 30 right-hand side of the bell.

I have described above the best way now known to me for embodying my invention, but I do not mean to limit myself to the exact construction shown in the drawings and 35 described in the specification except as required by the scope of the appended claims.

The dash-piston p plays another important part in the operation of my invention, especially when the valve v is located at a 40 considerable distance from the cylinder C, necessitating a long tube h or H.

It will be noted that when the striker S is in the position shown in full lines its weight tends to assist the motion of the piston on its upward stroke, whereas when it has 45 swung across to the other side of the fulcrum f to the position shown in dotted lines, its weight would tend to oppose the upward movement of the piston. This action, if not compensated for, would tend to retard the 50 motion of the striker in the latter part of its stroke, when it is especially necessary that it should move with its greatest speed and power. This compensating action is 55 provided for by the dash piston p.

When the valve v is opened, admitting 60 pressure under the piston P, it acts at first only on the annular area outside the piston p, which must be drawn out of the dash pot against the suction acting on the area of the 65 smaller piston p. This tends to delay the start of the piston until sufficient pressure has accumulated in the pipe H to overcome this suction. Then as soon as the piston p

of both large and small pistons is exposed to pressure, and the latter part of the stroke is made with increased force, thus insuring a sharp and powerful blow upon the bell.

Whereas I have described my bell as operated by code-signaling mechanism, it may be desirable to operate the same by other means. It is apparent that the cord w may be operated by hand or other means to move the piston v and operate the device. Such a 70 mode of operation might be particularly desirable were the code mechanism to get out of order or the power for actuating the same to fail, or not be available in an emergency.

Having thus fully described my invention, I claim and desire to secure by Letters Patent of the United States:—

1. In an apparatus for producing sound vibrations in water, the combination of a resonator in contact with the transmittory 85 liquid, a striker in operative relation to said resonator, a piston mechanically connected with the striker, whereby single strokes of the piston will produce corresponding strokes of the striker upon the 90 resonator, means for introducing a fluid under pressure behind said piston, a valve governing the action of said fluid, an elastic body operating to open the valve quickly in the direction required to cause a working 95 stroke of the striker upon the resonator, whereby a sharp stroke of the striker is secured, substantially as described.

2. In an apparatus for producing sound vibrations in water, the combination of a 100 resonator in contact with the transmittory liquid, a striker in operative relation to said resonator, a piston mechanically connected with the striker, whereby single strokes of the piston will produce corresponding 105 strokes of the striker upon the resonator, means for introducing a fluid under pressure behind said piston, a valve governing the action of said fluid, an elastic body adapted to open the valve quickly in the 110 direction required to cause a working stroke of the striker upon the resonator, means for moving the valve in the opposite direction, and for allowing the valve to be quickly released to the action of the elastic body, 115 whereby a sharp stroke of the striker is secured, substantially as described.

3. In an apparatus for producing sound vibrations in water, the combination of a 120 resonator in contact with the transmittory liquid, a striker in operative relation to said resonator, a piston mechanically connected with the striker, whereby single strokes of the piston will produce corresponding 125 strokes of the striker upon the resonator, means for introducing fluid under pressure behind said piston, a valve governing the action of said fluid, an elastic body adapted to open the valve quickly in the direction required to cause a working stroke of the 130

1
striker upon the resonator, a code wheel for
moving the valve in the opposite direction,
and for allowing the valve to be quickly re-
leased to the action of the elastic body at
5 predetermined intervals, said code wheel
being provided with removable stops whereby
a predetermined grouping of blows may
be delivered upon the resonator and corre-
sponding sound signals be produced in the
10 water, such grouping of blows being vari-
able according to the arrangement of said
stops.

4. In an apparatus for producing sound
vibrations in water, the combination of a
15 submerged resonator, a striker in operative
relation thereto, and a submerged piston
connected with the striker and means for in-
troducing fluid under pressure behind said
piston, a portion of the face of the piston
20 being unexposed to said fluid during the
first part of its working stroke and exposed
to said fluid during the latter part thereof.

5. In an apparatus for producing sound
vibrations in water, the combination of a
25 submerged resonator, a striker in operative
relation to said resonator, a piston positively
connected to said striker whereby said
striker and piston will move in unison,
means for introducing a fluid under pres-
30 sure behind said piston, a valve for govern-
ing the action of said fluid, a spring where-
by said valve may be opened instantane-
ously, and means for releasing and com-
pressing said spring periodically as de-
35 scribed.

6. In an apparatus for producing sound
vibrations in water, the combination of a
submerged resonator, a striker in operative
relation thereto, a submerged piston in op-
erative relation to the striker, said piston
40 having a projection of reduced area on its
lower end, a dash pot adapted to receive the
smaller end of said piston, a valve located
out of the water governing the action of a
45 fluid upon the piston, means for connecting
the valve with the submerged piston, and
means for controlling the operation of the
valve, whereby said fluid may be admitted
behind the piston at predetermined inter-
50 vals to cause a regulated succession of blows
to be delivered upon the submerged reso-
nator and corresponding sound impulses
produced in the water.

7. In an apparatus for producing sound
55 vibrations in water, the combination of a
submerged resonator, a striker in operative
relation thereto, a piston positively connect-
ed to said striker, and adapted to hold said
striker normally in inoperative position,
60 said striker being adapted to swing away
from said resonator when said piston falls,
a tube containing a liquid for operating the
piston, a valve located out of the water, for
governing the admission of a working fluid
65 to the upper portion of this tube, and means,

located out of the water, for controlling the
operation of the valve whereby it may be
caused to admit the working fluid to said
tube and piston at predetermined intervals
to cause a regulated succession of blows to 70
be delivered upon the submerged resonator
and corresponding sound impulses produced
in the water.

8. In an apparatus for producing sound
vibrations in water, the combination of a 75
submerged resonator, a striker in operative
relation thereto, a submerged piston in op-
erative relation to the striker, a tube contain-
ing a liquid for operating the piston, a valve
located out of the water, for governing the 80
admission and exhaust of a gaseous fluid
under pressure into and from the upper por-
tion of this tube, and means, located out of
the water, for controlling the operation of
the valve whereby it may be caused to admit 85
the working fluid to said tube and piston at
predetermined intervals to cause a regulated
succession of blows to be delivered upon the
submerged resonator and corresponding
sound impulses produced in the water. 90

9. In an apparatus for producing sound
vibrations in water, the combination of a
resonator adapted to excite sound vibrations
therein, a striker in operative relation to said
resonator, a piston mechanically connected 95
with said striker, whereby single strokes of
the piston will produce corresponding
strokes of the striker on the resonator, a
cylinder containing said piston a valve gov-
erning the action of a fluid upon the piston, 100
a portion of said piston and a portion of said
cylinder being of less diameter than the re-
mainder thereof as described whereby a por-
tion only of the active face of the piston is
exposed to the contacting fluid at the first 105
portion of the working stroke of the piston
and thereafter the entire face of said piston
is exposed.

10. In an apparatus for producing sound
vibrations in water, the combination of a 110
resonator adapted to excite sound vibrations
therein, a striker in operative relation to said
resonator, a piston mechanically connected
with the striker whereby single strokes of
the piston will cause corresponding strokes 115
of the striker upon the resonator, a tube for
introducing fluid under pressure behind the
piston, a valve governing the action of said
fluid, and means whereby a smaller area of
the piston is exposed to the action of said 120
fluid at the beginning of its stroke and the
area of the piston exposed thereto is there-
after increased.

11. In an apparatus for sending sound sig-
nals through water, the combination of a 125
resonator in contact with the water, a striker
in operative relation to said resonator, a
piston in operative relation to the striker,
said piston having an extension of smaller
cross-area than the main portion thereof to 130

- form a dash piston, a dash pot coöperating with said dash piston to allow an accumulation of pressure below said dash piston, means for introducing fluid under pressure behind the piston, a valve governing the admission and exhaust of said fluid to and from the piston, and means for controlling the operation of the valve as and for the purposes set forth.
- 10 12. In an apparatus for sending sound signals through water, the combination of a resonator in contact with the transmitting liquid, a striker in operative relation to said resonator and located to be swung to strike said resonator, a piston in operative relation to said striker, means for controlling the speed of movement of the piston whereby its effectiveness as a mover of said striker is increased as said striker approaches said resonator and means whereby a regulated succession of blows may be delivered by the striker upon the resonator and corresponding sound impulses produced in the water.
- 15 13. In an apparatus for producing sound vibrations in water, the combination of a resonator, a striker in operative relation to said resonator, and means for operating said striker comprising a piston having different diameters and a cylinder having diameters corresponding to those of said piston, and a

pipe connection located to deliver fluid under pressure to the cylinder whereby a portion of the piston will be exposed to the action of the fluid at the beginning of its stroke and the area of the piston so exposed will be 35 thereafter increased.

14. In an apparatus for producing sound vibrations in water, the combination of a resonator in contact with the transmitting liquid, a striker in operative relation to said resonator, a piston mechanically connected with the striker whereby single strokes of the piston will produce corresponding strokes of the striker upon the resonator, means for introducing fluid under pressure behind the 40 piston, a valve governing the action of said fluid, means for moving the valve in the direction to release the pressure on the piston and permit the back stroke of the striker, and means for storing energy during this 45 movement to open the valve quickly when released, whereby there will be caused a sudden increase of pressure upon the piston and a sharp stroke of the striker against the resonator, as described.

HORACE B. GALE.
